UNITED STATES PATENT OFFICE.

MARTHA N. LEONARD, OF WASHINGTON, DISTRICT OF COLUMBIA.

DESIGN FOR A LAMP SHADE.

Application filed September 18, 1925. Serial No. 14,808. Term of patent 3½ years.

To all whom it may concern:

Be it known that I, MARTHA N. LEONARD, a citizen of the United States, residing at Washington, District of Columbia, have invented a new, original, and ornamental Design for Lamp Shades, of which the following is a specification, reference being had to the accompanying drawing, forming part thereof wherein—

I claim:

The ornamental design for a lamp shade, as shown.

MARTHA N. LEONARD.
